[57] CLAIM

The ornamental design for a panel for a chair back, as shown and described.

DESCRIPTION

FIG. 1 is a front perspective view of the panel for a chair back showing our new design.

FIG. 2 is a top view of the same.

FIG. 3 is a bottom view of the same.

FIG. 4 is an end view of the same.

The reverse side of the panel is plain and unornamented.

FIG. 2

FIG. 1

FIG. 4

FIG. 3
